United States Patent Office

Des. 220,902
Patented June 15, 1971

220,902

BOTTLE OR SIMILAR ARTICLE

Jack H. Rosfeld and James C. McKinney, Greenville
County, S.C., assignors to Texize Chemicals, Inc.

Filed Apr. 8, 1970, Ser. No. 22,317

Term of patent 14 years

Int. Cl. D9—01

U.S. Cl. D9—42

FIG. 2

FIG. 1

FIG.5

FIG. 1 is an elevational view of a bottle or similar article showing our new design;

FIG. 2 is an elevational view looking from the right of FIG. 1, the opposite side being a mirror image of the side shown;

FIG. 3 is an elevational view of the side opposite the one shown in FIG. 1;

FIG. 4 is a top plan; and

FIG. 5 is a bottom plan view thereof.

We claim:

The ornamental design for a bottle or similar article, as shown.
